UNITED STATES PATENT OFFICE.

HARRY H. CLARK, OF BROOKLYN, NEW YORK.

DESIGN FOR A PORTABLE BOOTH.

Application filed June 9, 1927. Serial No. 22,375. Term of patent 14 years.

To all whom it may concern:

Be it known that I, HARRY H. CLARK, a citizen of the United States, residing at Brooklyn, in the county of Kings and State of New York, have invented a new, original, and ornamental Design for a Portable Booth, of which the following is a specification, reference being had to the accompanying drawing, forming part thereof.

The figure is a perspective view of a portable booth showing my new design.

I claim:

The ornamental design for a portable booth, as shown.

In testimony whereof I have signed my name to this specification.

HARRY H. CLARK.
